UNITED STATES PATENT OFFICE.

OWEN C. WATKINS, OF MIDDLETOWN, OHIO, ASSIGNOR OF ONE-HALF TO THOMAS E. REED, OF MIDDLETOWN, OHIO.

WEATHER-BOARDING GAGE.

1,229,356.

Specification of Letters Patent. Patented June 12, 1917.

Application filed December 13, 1916. Serial No. 136,751.

To all whom it may concern:

Be it known that I, OWEN C. WATKINS, a citizen of the United States, residing at Middletown, Butler county, Ohio, have invented certain new and useful Improvements in Weather-Boarding Gages, of which the following is a specification.

This invention relates to a tool designed to facilitate the accuracy and rapidity of the 10 work of weatherboarding, and will be readily understood from the following description taken in connection with the accompanying drawing in which:

Figure 1 is a perspective view of the 15 gage:

Fig. 2 an elevation of a structure being weatherboarded and illustrating uses of my improved gage: and

Fig. 3 an elevation of a single weather- 20 board illustrating a use of the gage.

A diversity of scales is employed in the drawing.

In the drawing:

1, indicates a vertical bar having a true 25 straight front edge or surface and having a true straight side edge or surface:

2, the side edge of the bar:

3, a first jaw disposed at the rear of the 30 bar and projecting sidewise from the side edge of the bar at right angles to that edge:

4, the front edge of the bar:

5, a front extension for the first jaw 3, the front surface of this extension being flush with the front surface 4 of the bar, 35 parts 3 and 5 causing the first jaw to have a fore-and-aft width equal to the width of bar 4 plus the portion of the first jaw 3 which projects rearwardly of the bar:

6, a second jaw projecting from the side 40 edge of the bar a distance equal to the side projection of the first jaw:

7, a third jaw at the rear of the bar and forming a prolongation of the first jaw in a direction opposite that in which the first 45 jaw projects, the lower surface of the third jaw 7 being flush with the under surface of the first jaw 3, the jaws 3 and 7 together forming a T-head at the rear of the upper end of the bar:

50 8, a spirit-level carried by the bar on the side opposite jaws 3 and 6 and having its axis parallel with the plane of the outer ends of those jaws:

9, a socket carried by the bar and adapted 55 to receive a pencil or scribe: and

10, a weatherboard.

I employ the terms front, side, upper, etc., for convenience in description with special reference to the gage as it appears in Fig. 1 of the drawing, it being understood that the 60 gage may be used in a variety of positions and that such expressions as have been mentioned are to be considered in their relative sense only.

The lower surfaces of jaws 3 and 7 are, 65 as have been stated, to be even with each other. The front surfaces of the bar and of jaws 6 and of jaw extension 5 are to be in a common plane, and the length of the bar between the upper and lower jaws should be 70 in excess of the width of the weatherboarding to be dealt with.

By hanging the gage upon the upper edge of a weatherboard, as in Fig. 3, its edge 2 forms the edge of a T-square at right angles 75 to its head. By giving the bar a quarter turn, on the rear corner of its edge 2 as an axis, the gage may hang upon the weatherboard in the position indicated at the left in Fig. 2, and in either position of the gage it may 80 be readily shifted along the weatherboard.

In cutting weatherboarding the first act is to square the end of the board, and in doing this it is usual to employ a try-square. In doing this work with my improved gage the 85 gage is applied as illustrated in Fig. 3, the jaws 3 and 7 forming the head of a T-square, the face 2 of the bar being at right angles to the under surface of the head. The weatherboard is then scribed along the 90 face 2. Fig. 2 illustrates a board as being fitted to go between a corner-board and a window-frame. In marking off the left-hand end of this board, the try-square would answer the purpose if the corner-board were 95 known to be plumb. But corner-boards and window-frames are often out of plumb and my gage is used instead of a try-square, as illustrated in Fig. 2. The board having been properly positioned vertically, the gage 100 is set with the jaws 3 and 6 against the corner-board, the gage straddling the weatherboard, and the weatherboard is then scribed along the face 4, the mark thus scribed representing a cut which will correspond with the corner-board regardless of whether the corner-board be plumb or not.

The procedure is the same in-scribing at the righthand end of the board, except that the gage is in this case reversed endwise so as 105 110

to bring the proper faces of the jaws against the window frame.

In weatherboarding it is customary to measure up from the bottom of the last board and temporarily set two nails to serve as rests for the board to be applied. If this plan be followed without any checking system the result may be an accumulative error as the work proceeds. My gage may be employed in leveling the board being applied, as illustrated in Fig. 2, the extremities of jaws 3 and 6 resting on the upper edge of the board being dealt with.

I claim:—

15 A weatherboarding gage comprising, a vertical bar having a true straight front edge and a true straight side edge, a first jaw disposed at the rear of the upper end of the bar and projecting transversely of the

side edge of the bar, a front extension of 20 said first jaw having its front surface in the plane of the front edge of the bar, a second jaw disposed at the lower end of the bar and projecting from the side edge of the bar a distance equal to the projection of the first 25 jaw from that edge and having its front surface in the plane of the front edge of the bar, and a third jaw disposed at the rear of the bar and projecting transversely of the bar in the direction opposite that of 30 the first jaw and having its lower surface in the plane of the lower surface of the first jaw and at right angles to the side edge of the bar, combined substantially as set forth.

OWEN C. WATKINS.
